SKIRT HANGER

Philip O. D'Ath, Bellflower, Calif.

Application June 11, 1954, Serial No. 30,947

Term of patent 14 years

(Cl. D80—8)

FIG. 1

To all whom it may concern:

Be it known that I, Philip O. D'Ath, have invented a new, original, and ornamental Design for a Skirt Hanger, of which the following is a specification, reference being had to the accompanying drawing, forming a part hereof.

I claim:

The ornamental design for a skirt hanger, substantially as shown.
